UNITED STATES PATENT OFFICE.

WILLIAM H. GRADY, OF LOUISVILLE, KENTUCKY, ASSIGNOR, BY MESNE ASSIGNMENTS, TO AMERICAN CREOSOTING COMPANY, OF LOUISVILLE, KENTUCKY, A CORPORATION OF DELAWARE.

RAILWAY CAR.

Application filed May 26, 1927. Serial No. 194,431.

This invention relates to a railway car, which because of its manner of use is termed a "shuttle car". The car has been designed and is particularly adapted for use in wood preservation plants in which cars loaded with pieces of wood, such as railway ties, poles, and the like, are run into cylinders in which the wood is impregnated with a preservative such as creosote.

10 These cars are provided with bolster arms for laterally supporting the load, which is held in place by bails curved to conform to the shape of the impregnating cylinder, as will be readily understood from Patent No. 15 1,428,474, patented Sept. 5, 1922, to Cook and Austen. These removable bails are provided with detachable fastenings for securing them to the bolster arms.

In practice a large number of these bolster 20 arm tram cars are employed in a wood preservation plant and are used, inter alia, in transporting the ties from the storage yard, which may cover many acres, to a wood-working plant in which they are adzed and 25 bored prior to impregnation. In thus transporting the ties, in order that increased loads may be carried, detachable arm extensions of the kind described in my application Ser. No. 185,502, filed April 21, 1927, are used.

30 In the cycle of operations, the cars loaded with ties are taken to the wood-working plant and unloaded, the arm extensions being removed. The cars are then loaded with the adzed and bored ties, the bails are applied, and the loaded cars are run into the impregnating cylinders, from which the still loaded cars are transferred to the shipping dock or platform, where the bails have to be and are removed, and the ties unloaded. The 40 cars are then again equipped with extension arms and go out into the storage yard for new loads. There is thus an accumulation of extension arms at the wood-working plant, and an accumulation of bails at the 45 shipping dock. In order to facilitate the transfer or interchange of the bails and extension arms from the places where they are not needed to the places where they are needed, I have devised a special form of car, 50 constructed and arranged to conveniently carry both the bails and the extension arms, a particular feature of the car being that the bails can readily be put on and taken off without liability of entanglement.

The construction of the car will be readily 55 understood from the accompanying drawings in which

Fig. 1 is an end view of one form of car;

Fig. 2 is a fragmentary plan view of an end portion of the car, some parts being 60 shown in section;

Fig. 3 is a side elevation of one of the two similarly constructed ends of the car;

Figs. 4, 5 and 6 are similar views of a modified form of car; and 65

Figs. 7 and 8 are respectively diagrammatic end and side views of the car showing the manner in which the bails and extension arms are carried on the cars.

Referring to Fig. 1, the frame work of the 70 car, having the usual running gear, comprises transverse and longitudinal beams 2, which support the floor 3. Extending upwardly from the floor are a series of arched angle irons 4 having substantially the same 75 curvature as the bails 6, to which is secured a curved sheet-iron cover 5. At the ends of the top or peak of the cover are provided upstanding lugs 12 to prevent the bails from sliding off.

80 Located at each side of the car are pockets 7 the bottoms of which are extensions of the bottom plate, and the sides upwardly extending plates 8. Partition 20 may be provided between the pockets. End plates 9 extend 85 across the ends of the car.

The ends of the bails when mounted on the car extend into these pockets which also serve to catch and retain bale pins, fastenings and other small articles.

90 Hooks 10 are secured to beams 2, to facilitate shifting of the cars.

In the modified form of cars shown in Figs. 4, 5 and 6, the roof or cover is gable-shaped instead of curved, the construction 95 being otherwise the same. Corresponding parts of this modified form are marked with the same reference letters, except that the inclined supporting beams are marked 4*. In both forms the sides of the cover are inclined, being curved in the one case and straight in the other. The manner of use will be apparent from Figs. 7 and 8.

100 The bails 6 are placed astride the saddle top, with their ends extending into the pockets, so that they can not slide out of position. The lugs 12 prevent them from being dislodged endwise during transporta-

tion, and the inclined cover or roof 5 guides the ends of the bails as they are dropped down, and prevents the ends of the bails from entering the interior of the car. The 5 interior of the car under the roof serves to receive the extension arms 13 as shown in Fig. 7, the end pieces 9 serving to prevent the interior load from sliding out.

I claim:

- 10 1. A car having a closed cover or roof extending upwardly from the floor, the sides of the cover being inclined, upwardly extending lugs at each end of the top of the cover, and a floor extending beyond the sides 15 of the cover.

2. A car as claimed in claim 1 in which the cover is curved to the approximate curvature of the article, such as a bail, to be carried thereon.

3. A car as claimed in claim 1 in which 20 pockets are constructed on the part of the floor extending beyond the cover.

4. A car as claimed in claim 1 in which 25 pockets are constructed on the part of the floor extending beyond the cover, and end plates extend across the ends of the car.

In testimony whereof, I affix my signature.

WILLIAM H. GRADY.
